UNITED STATES PATENT OFFICE.

ALBERT FREMONT, OF PARIS, FRANCE.

STAPLING MACHINE.

Application filed November 22, 1924, Serial No. 751,698, and in France October 24, 1924.

This invention relates to a machine intended for mechanically stapling together two thicknesses of material, especially thicknesses of leather in the manufacture of travelling bags or the like.

The characteristic feature of the invention consists in the attachment of the staples in a single operation, automatic charging means being provided for feeding a staple 10 in front of each hammer so that the machine is always ready for use.

The annexed drawings show by way of example one method of carrying the invention into practice, but it is to be clearly 15 understood that the machine may be modified as to a whole or as to the details hereinafter described according to the class of work to be carried out.

In the accompanying drawings:—

20 Fig. 1 is a plan of the machine.

Fig. 2 is a front elevation.

Fig. 3 is a side elevation with parts in section.

25 Fig. 4 is a part section of a feeding vice.

Fig. 5 is a section on the line C—D of Fig. 4.

30 Figs. 6 and 7 are sectional details of the feeding device, taken on the lines A—B and C—D respectively of Fig. 4.

Fig. 8 is a detail side elevation and plan view of the pressing plunger of the staple feeding magazine.

Fig. 9 is a view of the mechanism for 35 opening the feeding devices so as to allow for the insertion of the portions of the bag or the like which have to be attached together.

Fig. 10 is a front view of the back plate 40 which constitutes an anvil and causes the ends of the staples to be turned over.

The machine comprises a main framework 1, which may be a casting, the sides of which are parallel and provided with two dove-tail guides 2 and 3. On these guides is 45 adapted to slide a carriage 4 carrying a series of driving hammers 5, which are easily interchangeable. These hammers consist each of an elongated steel plate. They 50 are intended to force the staples through the thicknesses of leather and into contact with an anvil 14 which turns over their extremities so as to obtain a perfect attachment of the parts together.

55 The carriage 4 carrying the hammers is operated by a shaft 6 having an external

screw thread 7 of steep pitch screwing into the internally screw threaded nut member 8 connected to the carriage.

The shaft 6 is supported towards its rear end by a bearing 9 allowing for rotary but not for longitudinal movement. It is provided with a worm wheel 10 operated by the worm 11, which latter is operated by the shaft 12 carrying the fly wheel 13.

As will be seen, a simple operation of the fly wheel 13 causes the carriage 4 and the hammers 5 to move forward to do their work. The number of the hammers varies according to the size of the bags or the like 70 to be manufactured.

The extremities of the staples are turned over by means of the back plate 14 (Fig. 10) in which are provided a plurality of hollow recesses 15, one corresponding to each hammer. This back plate may be cast with the framework and is so shaped as to facilitate the reception on the inner face thereof of one of the folded pieces of leather or the like.

80 The back plate 14, carries a spindle 16, provided with a certain number of cams 17, which are rotated by turning the spindle 16, by means of a handle 18. A plurality of carriers 19, pivotally mounted at one of their ends upon a shaft 20, extends substantially in parallelism with the anvil 14, each of said carriers having secured thereto a staple magazine 24. A carrier 19 and magazine 24 is provided for each hammer 5, and a cam 90 17 is provided for each carrier. The cams 17 are normally secured to the spindle 16, but are relatively adjustable thereon. The foregoing construction enables the workmen to rotate the spindle 16 to bring the cams 17 successively into engagement with the carriers 19, causing said carriers to be moved, one after the other, thus moving away the various groups of feeding devices from the anvil and facilitating the insertion of the 100 pieces of leather or the like which are to be attached together.

When one of the cams ceases to operate, a pull spring 21 brings the carrier 19 towards the anvil, thus closing the jaw-like 105 opening formed between the carrier and the anvil, whereby the leather is clamped between the anvil 14 and the extremities of a staple guiding member 22 which serves to guide the staples 23 at the moment they are 110 forced forward by the hammer 5.

When one of the staples has been fed in

front of a hammer 5, by mechanism presently to be described, a simple operation of the fly wheel 13 causes the carriage 4 to be actuated and to move towards the anvil, carrying with it the plurality of hammers and causing the whole series of staples to penetrate the leather simultaneously, the extremities of the staples being then turned over in the recesses 15 of the anvil 14.

10 The magazine or feeding device for the staples is shown in Figs. 4, 5, 6, 7 and 8. Each magazine preferably consists of a sheet metal tube 24 of square cross section from one side of which a pair of longitudinally extending wings project. These wings, which are also of sheet metal are adapted to be bent into engagement with the inclined sides of the carriers 19, as shown in Fig. 5, thus serving to connect the magazine in dove 15 tail engagement with its respective carrier. Each carrier 19, as clearly shown in Figs. 4, 5 and 6, consists of two spaced parallel members, one of which is engaged by the cam 17 and has the magazine tube 24 secured thereto, as described above, while the other member to which the reference character 19^a is applied, is spaced slightly below the magazine tube 24 and serves as a support for the connecting leg of the staples. As shown in 20 Fig. 6, this connecting leg of the staples is located between one of the sides of the magazine tube, while the pointed prongs of the staples extend about the two adjacent sides of the tube. Each magazine is provided at 25 its outer end with a small, channelled, staple-feed or guiding member 22, suitably secured to the magazine tube 24, and having its inner face slotted or otherwise provided with an opening through which the staples 23 are 30 fed into the interior of the guiding member.

The movement of the staples 23 into the guiding member 22 is obtained by means of a helical compression spring 26 located in the interior of the magazine 24. This spring 45 26 pushes forward a plate 27 provided with three fingers or extensions 28 which slide along three grooves 29 provided on the three faces of the magazine 24.

The plate pushes the staples progressively 50 so that the latter come one by one against the wall of the channel formed in the guiding member 22 and in front of each hammer.

The invention also contemplates the employment of staples of larger size. For instance, the staples may be of curved shape 55 for fastening together curved portions of the bag or the like.

Moreover where the portions of the bag or the like are rounded, the staples may be of

corresponding shape. Generally, they may 60 be bent in any manner to conform to the shape of the parts for which they are to be used. They may be constituted of stampings in metal provided with gripping tongues, or fixed by means of smaller staples. 65

What I claim and desire to secure by Letters Patent in the United States of America is:—

1. In a machine for stapling together thicknesses of material, especially leather, 70 the combination of a framework, an anvil carried by the said framework, a carriage adapted to reciprocate with respect to the said anvil, a plurality of hammers attached to the said carriage, means for reciprocating said carriage, and a plurality of staple carrying magazines, one for each of said hammers, pivotally secured to said anvil. 75

2. A machine, as set forth in claim 1, in which each of the magazines is provided with a staple guiding member having a channel in alignment with its respective hammer, through which the hammer is adapted to be moved by the reciprocation of said carriage to force the staples through the material and clinch them against the anvil. 80 85

3. In a machine as claimed in claim 1 a construction in which the carriage carrying the hammers is operated by means of a shaft rotatable but not longitudinally slidable in 90 the framework, the said shaft being provided with a screw threaded portion engaging a nut member on the carriage, together with means for rotating the said shaft such as a worm wheel thereon meshing with a worm 95 on another shaft, which latter shaft is provided with a fly wheel, substantially as described.

4. A machine as set forth in claim 1, in which are provided, a plurality of springs 100 for normally urging the magazines toward the anvil to clamp the material against said anvil, cams for moving said magazines away from said anvil, and means for actuating said cams. 105

5. In a machine as claimed in claim 1 a construction in which the magazine feeders for fastening devices are pivotally mounted so that they can be moved away from the anvil, with means such as a spindle on the 110 fixed framework carrying cams for moving the feeding devices away from the anvil when required, and spring means for bringing the feeding devices back to their normal positions substantially as described. 115

In testimony whereof I have affixed my signature.

ALBERT FREMONT.
